UNITED STATES PATENT OFFICE.

HENRY J. FRANTZ, OF METAMORA, ILLINOIS, ASSIGNOR OF ONE-HALF HIS RIGHT
TO WILLIAM B. WHIFFEN, OF SAME PLACE.

DESIGN FOR CATTLE-HORN KNOBS.

Specification forming part of Design No. 5,136, dated July 25, 1871.

To all whom it may concern:

Be it known that I, HENRY J. FRANTZ, of Metamora, in the county of Woodford and in the State of Illinois, have invented a new and Improved Design for Knobs for the Horns of Cattle; and do hereby declare that the following is a full, clear, and exact description thereof, reference being had to the annexed drawing making a part of this specification, in which like letters of reference refer to like parts, and in which—

Figure 1 represents a perspective view, showing the top end of the knob; Fig. 2, a perspective view, showing the bottom end of the same; and Fig. 3, a view of all the sides of the knob, showing the initial letters or characters as they appear on each side.

The design of this invention consists in forming, on cattle-horn knobs of the ordinary construction, a letter or the initial of the name of

the owner of the animal, so as to indicate some distinguishing-mark by which the animal may be clearly identified.

The accompanying drawing will indicate fully the nature of this design without further description.

Having thus fully described my invention, what I claim therein as new, and desire to secure by Letters Patent, is—

The design for cattle-horn knobs, substantially as shown and specified.

In testimony that I claim the foregoing as my invention I have hereunto set my hand this 28th day of April, 1871.

HENRY J. FRANTZ.
